UNITED STATES PATENT OFFICE.

SANFORD W. STORMS, OF TARRYTOWN, NEW YORK.

WINDOW SHADE AND CURTAIN HOLDER.

1,187,199.

Specification of Letters Patent. Patented June 13, 1916.

Application filed January 7, 1916. Serial No. 70,851.

To all whom it may concern:

Be it known that I, SANFORD W. STORMS, a citizen of the United States, residing at Tarrytown, in the county of Westchester and State of New York, have invented new and useful Improvements in Window Shade and Curtain Holders, of which the following is a specification.

This invention relates to a combined window shade and curtain pole support and it has for its principal object the provision of a device of this character which will be simple, strong and durable and, one which will be capable of being adjusted whereby it may properly accommodate itself to shade rollers of different lengths.

As another object in view I aim to provide a device of this character which will eliminate the necessity of unduly marring the window frame, incident to the necessity of applying shade rollers of different lengths to the frame.

A still further object of the invention resides in the provision of a combined shade roller bracket and curtain pole support which will include an adjustable hanger for the roller and a support for the curtain pole, co-acting with the hanger to hold the same against being accidentally shifted from its intended position and thereby positively insure retention of said hanger against the trunnion of the shade roller.

In the drawings forming a part of this specification and in which like reference numerals indicate similar parts throughout the several views: Figure 1 is a perspective view of a portion of a window frame showing the application of the bracket thereto. Fig. 2 is a vertical section through the same. Fig. 3 is a horizontal section taken on the line 3-3 of Fig. 2.

The combined shade roller support and curtain pole hanger, consists of a bracket member 1, which is stamped from a single piece of sheet metal, provided with right angular ends 2-2, attaching flanges 3-3 and a relatively long horizontal connecting portion 4 between the branches 2-2. This connecting portion has a longitudinal slot 5 formed therein for a purpose to be herein-after referred to. The bracket is adapted to be secured to one side of the window frame by means of screws or similar fastening devices 6. When applied in this manner, the slotted connecting portion 4, between the branches 2-2 will be spaced from the inner

face of the window frame as clearly shown in Figs. 2 and 3.

The shade roller hanger 7 is suspended from the intermediate portion 4 of the bracket and the upper end of said hanger is extended against the rear surface of said portion 4 and it is adapted to be brought into clamping contact therewith by means of a clamping screw 8. This screw passes through the slot 5 from the front of the bracket and connected with the screw is a washer 9 and a binding or clamping nut 10. The upper extremity of the hanger 7 and the portion 4 of the bracket 1, are thus operatively interposed between the washer 9 and the mentioned nut 10 and by turning the screw, one may readily effect freedom of the hanger 7 relatively of the portion 4 of the bracket and thus permit the former to be moved to the requisite position upon said portion 4 as will be clearly understood. It will be appreciated that I intend using the brackets in sets of two, arranging the same along the same horizontal line upon the window frame, and incident to the described construction of the bracket and its hanger, it is evident that a shade roller of any given length may be operatively accommodated without necessitating a change in the position of the bracket upon the frame. When it is desired to adjust the shade roller to the hangers 7, the screws 8 are released and the hangers then moved to points upon the brackets where they may operatively accommodate themselves to the trunnions on the ends of the shade roller. The lower extremities of the hangers 7 are bent over in hook shaped formation as shown in Fig. 2 so as to receive the end trunnions of said roller.

It of course, is observed, that in so forming the hooks on the lower extremities of the hangers, such regard will be given to either formation as to permit one of the hangers to fixedly engage with the usual rectangular trunnion of the shade roller with which the ordinary tension spring of the roller is connected.

In order that the hanger 7 may be held against swinging from the bracket, use is made of a curtain pole support 11 which consists of a horizontal shank 12 having a screw thread 13 which may be engaged in the window frame, see Fig. 2. This shank is adapted to be passed through the receiving shoulder 14 in the hanger, and it is preferred to provide the shank with a stop lug

15 which may be brought into clamping contact with the hanger. The curtain pole support 11 extends forwardly in advance of the hanger and it is provided at its free end, 5 with a terminal vertically disposed extension 16 for accommodating the curtain pole in the usual manner. By extending the shank 12 through the aperture 14 as described, the lower hook shaped portion of 10 the hanger is securely confined against the trunnion and possibility of the latter slipping from the hanger is reduced to a minimum.

What is claimed as new is:—

- 15 A shade roller and curtain pole bracket, comprising, a slotted member adapted to be secured to the frame and provided with portions for spacing the same from the frame, a hanger movable along the slotted 20 portion, means passing through said slotted

portion and through the hanger for suspending the latter from said slotted portion and for initially defining adjustment of the hanger relatively of the shade roller, means on the hanger for receiving the trunnion of the shade roller, and a curtain pole supporting device passing through the hanger and adapted to be extended into the frame and serving to retain the hanger in this adjusted position upon said slotted portion and to 25 hold the trunnion receiving means of the hanger against accidental derangement from the trunnion.

In testimony whereof I affix my signature and in presence of two witnesses.

SANFORD W. STORMS.
